UNITED STATES PATENT OFFICE.

THOMAS A. REID, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC RESISTANCE FURNACE.

Application filed June 15, 1921. Serial No. 477,623.

To all whom it may concern:

Be it known that I, THOMAS A. REID, a citizen of the United States, and a resident of Pittsburgh, in the county of Allegheny and State of Pennsylvania, have invented a new and useful Improvement in Electric Resistance Furnaces, of which the following is a specification.

My invention relates to electric furnaces and particularly to electric-resistance furnaces, and it has for its object to provide a relatively simple and easily installed resistor-supporting means.

In practicing my invention, I provide a plurality of flat refractory members having tongue-and-groove edges adapted to inter-fit with each other and having also a plurality of integral projections on one surface. The plates are so combined as to form a substantially self-supporting arch which is located in the furnace chamber. A plurality of arches so formed are located in spaced-apart relation, and a metallic resistor member of relatively large cross-sectional area, so formed as to comprise a plurality of parallel extending end-connected convolutions, is supported adjacent the furnace-chamber walls by the said arches.

In the single sheet of drawings, Figure 1 is a view, in lateral vertical cross-section, of an electric furnace comprising the device embodying my invention;

Fig. 2 is a view, in vertical longitudinal section on the line II—II of Fig. 1;

Fig. 3 is a view, in side elevation, of a single resistor-supporting plate embodying my invention, with a portion of the resistor element in its operative position, and

Fig. 4 is a view, in side elevation, of the parts illustrated in Fig. 3.

An electric-resistance furnace 5 comprises, in general, a suitable metal casing 6 provided with suitable supporting members 7.

A lining 8, surrounding the furnace chamber 9, comprises a plurality of suitably shaped bricks or blocks of any suitable refractory material usually employed in electric furnaces. While only a single-layer lining is illustrated in Figs. 1 and 2, it is to be understood that this lining may have any desired or necessary number of layers to accomplish the purpose desired.

At the bottom of the furnace chamber 9 is located a plurality of resistor-supporting members 10 which are substantially the

same as those disclosed in application Serial No. 449,685, filed jointly by O. A. Colby and myself, on March 5, 1921. Each of the members 10 comprises a flat refractory plate having a plurality of alined integral projections on one surface thereof, a resistor member 11 being maintained in its proper operative position by means of single projections.

A plurality of substantially flat refractory resistor-supporting members 12 are provided, one thickened edge having a tongue and an opposite thickened edge having a cooperating groove therein. A plurality of alined integral projections 13 are located on one surface of the plates 12. The plates 12 may be relatively narrow and elongated, and the tongue and groove edges may be so arranged as to permit of combining a plurality of members 12 to form a complete and substantially self-supporting arch inside of the furnace chamber, substantially as illustrated in Fig. 1. The surface of the members 12, upon which are located the projections 13, faces the wall, and the projections cooperate with the surface of the wall to maintain a resistor member 14 in its proper operative position in the furnace chamber. The resistor 14 comprises a metallic bar, wire or rod of relatively large cross-sectional area and is so formed as to consist of a plurality of straight parallel-extending and end-connected convolutions.

The built-up arches, each comprising a plurality of plates 12, are located in spaced apart relation in the furnace chamber, substantially as illustrated in Fig. 2; and the resistor 14 is of large enough cross-sectional area to be substantially self-supporting between the successive and adjacent arches.

It may be noted that the device embodying my invention provides a relatively simple and easily manufactured refractory resistor-supporting member, a plurality of which may be combined to form a substantially self-supporting arch in the furnace chamber and to have provision for maintaining the parts of a cooperating resistor member in proper operative position relatively to each other and in the furnace chamber.

Various modifications may be made in the device embodying my invention without de-

parting from the spirit and scope thereof, and I desire that only such limitations shall be placed thereon as are imposed by the prior art or are specifically set forth in the 5 appended claims.

I claim as my invention:

1. An electric furnace comprising a plurality of spaced-apart sets of refractory resistor-supporting plates combined to form 10 substantially self-supporting arches, the plates in each set having interfitting tongue-and-groove edges, and directly supporting an electric resistor.
2. An electric furnace comprising a plurality of refractory walls and a plurality of sets of refractory resistor-supporting plates, the plates in each set being combined to form a substantially self-supporting arch independent of said refractory walls, the 20 plates having a plurality of alined integral projections on one surface thereof and interfitting tongue-and-groove edges.
3. An electric furnace comprising a plurality of spaced-apart sets of relatively narrow refractory resistor-supporting plates combined to form substantially self-supporting arches, the plates having a plurality of alined integral projections on the inner surface thereof and interfitting tongue-and- 25 groove edges, and a resistor member directly supported by said plates and comprising a plurality of integral end-connected convolutions which are maintained in spaced relation thereon by means of said projections.
- 35 4. An electric furnace comprising a plurality of sets of interlocking relatively narrow refractory plates combined to form substantially self-supporting arches, each plate having a plurality of alined integral projec-

tions on one surface thereof, and a resistor 40 member having a plurality of end-connected parallel-extending convolutions maintained in operative positions, relatively to each other, by said projections, the width of said plates being such as to extend over only a 45 relatively small part of said convolutions, the resistor being substantially self-supporting between said sets of plates.

5. An electric furnace comprising a metallic resistor member having a plurality of parallel-extending, end-connected convolutions, and a plurality of spaced resistor-supporting arch members, each arch member comprising a plurality of refractory plates having interfitting tongue-and-groove edges 55 and a plurality of alined integral projections on one surface adapted to maintain said convolutions in proper operative positions relatively to each other, the resistor being substantially self-supporting between 60 said arch members.

6. In an electric furnace, in combination, a plurality of refractory walls defining a furnace chamber, a plurality of sets of relatively narrow resistor-supporting members, 65 the members of each set being interlocked with each other to constitute self-supporting arches substantially independent of said refractory walls, and a relatively heavy resistor member supported by said sets of refractory members and being substantially self-supporting therebetween and therebeyond.

In testimony whereof, I have hereunto subscribed my name this 3rd day of June 75 1921.

THOMAS A. REID.
